UNITED STATES PATENT OFFICE.

JOHN N. CLARKE, JR., OF CINCINNATI, OHIO.

HORSESHOE-MACHINE.

SPECIFICATION forming part of Letters Patent No. 325,054, dated August 25, 1885.

Application filed December 20, 1884. (No model.)

To all whom it may concern:

Be it known that I, JOHN N. CLARKE, Jr., a citizen of the United States, and residing at Cincinnati, in the county of Hamilton and State 5 of Ohio, have invented certain new and useful Improvements in Horseshoe - Machines, of which the following is a specification.

My invention relates to improvements in machinery for making horseshoes, or more especially to the dies used for bending, shaping, and punching the shoe, all of which will be fully hereinafter described.

In the accompanying drawings, Figure 1 is a plan view of the operative parts of my invention claimed herein, showing the die and rollers employed in bending a blank bar into shape, a blank bar being shown in dotted lines in position preparatory to bending. Fig. 2 is a longitudinal vertical section on line *xx*, Fig. 20. Fig. 3 represents broken side elevations of the punches used in making the nail-holes. Fig. 4 is a longitudinal elevation of one form of blank bar that my machine is preferably designed to shape. Fig. 5 is a plan of the 25 blank bar shown in Fig. 4. Fig. 6 is a detail perspective view of a detachable die-stock and one form of die used solely for bending the blank bar. Fig. 7 is a plan of the die shown in Fig. 6. Fig. 8 is a plan of a die used for 30 both bending and otherwise shaping the shoe, showing a series of punches therein for making the nail-holes. Fig. 9 is a longitudinal sectional elevation of the die shown in Fig. 8, taken on mixed line *yy* thereof. Fig. 10 is a 35 central longitudinal section of the die shown in Figs. 8 and 9 without the punches.

A represents the base or bed-plate of the machine, having supports *a a'*, and provided with the longitudinal irregular slots or ways 40 *A'* at either side its center.

B represents a reciprocating carriage or frame, suitably mounted so as to slide upon the bed-plate *A*.

B' B' are pitmen connecting with the frame 45 *B* by means of the wrist-pins *b b*, projecting laterally therefrom. These pitmen are shown broken off in Fig. 1; but it is clear without further illustration that they may be connected with a crank-shaft or other driving mechanism for operating the bending-frame *B*.

C C' represent slotted transverse bars, being

parts of the frame *B*, and having the bending-rollers *c c'* suspended beneath the upper bar, *C*, as shown in Fig. 2.

c'' represents rollers surmounting the bending-rollers *c c'*. 55

D D' represent slides moving laterally in the slots of the transverse bars *C C'*.

d d are bolts passing downwardly through slides *D D'*, and the rollers *c c' c''* serving as 60 journals for said rollers and securing the adjoining parts together. The bending-rollers *c c'* travel in the ways *A'* in the movements of carriage *B*, and are thereby guided to properly bend the blank bar into shape. The rollers *c''* being of greater diameter than the adjoining bending-rollers they pass freely along the upper face of the blank bar, and at the same time prevent any upward movement or buckling of said bar during the bending operation. 70

E represents a roller, journaled at its ends in boxes upon the carriage *B*, and provided with pinions *e e*, which are keyed thereon and engage rack-teeth *e' e'* on the upper face of 75 the bed-plate to revolve said roller at the requisite time, as hereinafter specified.

F represents a squeezing-die, constructed on or attached to the periphery of roller *E* intermediate its ends, and having the same 80 shape as the shoe to be made.

G represents the die around which the blank bar is bent. In Figs. 1 and 2 it is shown projecting upward from its base-plate *g*, which fits a cavity in the face of bed-plate *A* 85 between the curved portions of the ways or slots *A'*. Base-plate *g* of die *G* is detachably secured in place by the bolts *g'*.

G' represents a shouldered edge or flange along the sides of the die, for receiving the inner shouldered edge of the blank, and *H H* are wings projecting laterally from said die to provide a bearing above the plane of the base-plate for that part of the blank bar that lies between the toe and heel calks. The opening 90 *h* at the front of the die between said wings is provided to receive the toe-calks of the bar. 95

The wings *H* are cut away at their rear ends, forming shoulders *h'*, which permit the heel-calks of the blank to pass inwardly toward the 100 die without interruption in the bending operation.

In Fig. 6 I have shown the bending-die G so mounted upon its base-plate g that it can be adjusted thereon, and thereby adapt it to any possible variations or inaccuracies in the 5 construction or movements of the bending-carriage B. This manner of mounting the bending-die is a convenient one, as dies of different configurations can be readily exchanged one for the other, making it necessary for but 10 one die-base, g, to be used. The bottom of the die is supplied with a dovetail tongue, I, which fits a corresponding groove, I', in the face of the base-plate. A slot, i, is cut in said base through which the bolts i' pass for securing 15 the die in the desired place.

In Fig. 8 I have shown a die that is adapted for bending and otherwise shaping and finishing the shoe; but I prefer its use in connection with the roller-die F (shown in Figs. 1 20 and 2) and the male drop-die (shown in Fig. 8) after the blank bar has been bent.

The die-stock or base-plate is recessed at M to receive the bent blank bar m m' being cavities for containing the toe and heel calks 25 thereof.

1 2 3 4 represent upright punches, arranged in series and suitably set in the channel M at either side the toe-cavity m, for making the nail-holes in the shoe.

30 The operation of punching the bent blank bar is performed by the squeezing-roller die F, which immediately follows the bending operation, when the die shown in Fig. 8 is placed in position on the bed-plate. The squeezing-die 35 F acts upon the blank when the pinions e e on roller E engage the racks e' on the bed-plate A. The outer and inner faces of the points of the punches 1 2 3 4 are constructed at varying angles, as shown in Fig. 3, so as to 40 punch the nail-holes correspondingly, and thereby make provision for the varying angles in the shape of the animal's hoof.

The use of the double set of punches, one 45 at either side the toe-calk, with their points constructed as shown, is an important feature of my invention, as all the nail-holes can be punched simultaneously and uniformly. It is obvious that instead of arranging said punches in the die itself they could be mounted in line 50 in a head and used to punch the blank bar previous to bending it. The latter mode of mounting the punches would be preferable, because their points could be kept cool more readily by small jets of water than they could 55 be in the shaping-dies, as the blank bar is heated for operation in my machine.

When the die shown in Fig. 8 is used as a bending-die prior to punching or otherwise finishing the blank bar therein, the rear face of the base-plate is constructed at a lower 60 plane than the body thereof, leaving the shoulders h" like unto the shoulders h' on the die-plate shown in Fig. 1, both in form and purpose.

In Figs. 4 and 5 I show a blank bar adapted 65 for use in the dies shown and described herein; but it is obvious that a plain bar, without the openings or spaces between the toe and heel calks, or any bar used for making horseshoes, could be operated upon with but little alteration 70 in the construction of the dies and without departing from the principle of my invention herein specified. If a plain blank bar should be used, the squeezing-die F would 75 press it into the recessed die shown in Fig. 8 and thereby form the nail-holes, creases, and toe and heel calks thereon.

I claim—

1. In a horseshoe-machine, the combination, 80 with a stationary base plate, A, having the irregular slots or ways A' A', the die G, mounted thereon intermediate the slots A', and the rack-teeth e' e', of a reciprocating carriage, B, provided with slotted transverse bars C C', bending-rollers c c", suspended from and operating laterally in the slots of said bars C C' by 85 means of said ways A', and the roller E, having pinions e e, and squeezing-die F, all constructed and adapted to operate substantially as herein set forth.

2. The combination, with the shaping-die G, having recess or channel M and calk-cavities m m', of the dotters or punches 1 2 3 4, arranged and adapted to operate in connection with a squeezing-die, F, substantially as and for the 95 purpose specified.

3. In a horseshoe-machine, the dotters or punches 1 2 3 4, having their respective points constructed at varying angles to form simultaneously and uniformly the nail-holes in the 100 shoe to suit the varying angles in the shape of the horse's hoof, substantially as herein set forth.

In testimony of which invention I hereunto set my hand.

JOHN N. CLARKE, JR.
